UNITED STATES PATENT OFFICE.

LOUIS H. KNAPP, OF PARKERSBURG, WEST VIRGINIA.

MOLD FOR CASTING CENTER-HUNG SASH-WEIGHTS.

No. 812,935.

Specification of Letters Patent.

Patented Feb. 20, 1906.

Application filed March 28, 1905, Serial No. 252,605.

To all whom it may concern:

Be it known that I, LOUIS H. KNAPP, a citizen of the United States, residing at Parkersburg, in the county of Wood and State 5 of West Virginia, have invented a new and useful Mold for Casting Center-Hung Sash-Weights, of which the following is a specification.

This invention relates to certain improvements in molds, more particularly to a novel form of mold especially designed for molding center-hung sash-weights.

The object of the invention is to provide a simple, durable, and efficient mold of this 15 character, preferably formed in three sections, two of which are movable laterally to operative and inoperative positions upon the third.

A further object is to provide means for 20 cooling the several sections of the mold during the pouring or casting operation by passing a stream of water or other cooling medium through said mold-sections, thereby preventing excessive heating of the latter 25 and permitting the continuous operation of the mold.

With these and other objects in view the invention consists in the construction and 30 novel combination and arrangement of parts hereinafter fully described, illustrated in the accompanying drawings, and pointed out in the claim hereto appended, it being understood that various changes in form, proportions, and minor details of construction may 35 be resorted to without departing from the principle or sacrificing any of the advantages of this invention.

In the accompanying drawings, forming a 40 part of this specification, Figure 1 is a front elevation of a mold constructed in accordance with my invention, showing the several sections in position for molding or casting the sash-weights. Fig. 2 is an end view of the same. Fig. 3 is a transverse sectional view taken on the line 3 3 of Fig. 1. Fig. 4 is 45 a side elevation, partly in section, of a center-hung sash-weight made by the mold shown in Fig. 1.

Similar numerals of reference indicate 50 corresponding parts in all the figures of the drawings.

The improved mold is particularly designed for manufacturing what are commonly called "center-hung sash-weights," 55 and to this end the device comprises a base or stationary mold-section 5 and a pair of

movable mold-sections 6 and 7, the latter being constructed exactly alike and movable laterally on the base 5 to operative and inoperative positions. 60

The movable sections are each provided with a plurality of spaced vertically-disposed grooves or channels 8, adapted to register with each other when said sections are moved to closed or operative position to thereby 65 form molding compartments or chambers 9, into which the molten metal flows from the pouring-basins 10 through the gates 11.

The groove or channel 8 of one movable mold-section is provided near its lower end 70 with a lateral projection or core 12, which extends partly across the molding-compartment and engages a vertically-disposed core member 13, secured to or formed integral with the base or stationary mold-section 5. 75 The projection or core 12 is designed to form the recess 14 in the sash-weight 15, while the core 13 forms the central opening 16, which communicates with the recess 14 and is designed to receive the supporting-cord by 80 which the weight is suspended from the window-sash. The cores 12 are preferably curved, as indicated at 17, while the free ends of the cores 13 are reduced, as shown at 18, to render the adjacent walls of the central 85 opening curved or rounded, so as to prevent cutting or otherwise injuring the supporting-cord.

Secured to the opposite ends of the movable mold-sections are laterally-extending 90 lugs 19, over which suitable links 20 are placed, the latter being fitted with clamping-screws 21, adapted to engage the flat side faces of the lugs and by means of which the two sections are or may be securely locked 95 together during the pouring or casting operation.

The sides of the sections 6 and 7 are preferably formed with spaced ears 22, between which are mounted for rotation suitable 100 wheels or rollers 23, which bear upon the upper flat surface 24 of the base or stationary mold-section and facilitate the lateral movement of the former. Secured to the sections 6 and 7 and arranged in vertical alinement 105 with the ears 22 are lateral extensions 25, each provided with an inclined slot or recess 26, adapted to receive a lever or bar, so that by inserting one end of the bar or lever in the recess and exerting a lateral pull on the opposite end thereof the sections 6 and 7 may be 110 moved to inoperative position to permit the

discharge of the molded product without danger of burning or otherwise injuring the hands of the operator.

- As a means for cooling the movable sections during the pouring or casting operation I provide the same with a plurality of spaced horizontally-disposed passages or flues 27, each provided with an inlet 28 and an outlet 29 and through which water or other cooling medium is adapted to circulate. One or more similar passages or flues 30 may also be formed in the base or movable section 5, if desired, in order to keep the latter cool. By having the water circulate through the flues or water-passages in the several mold-sections the latter are prevented from becoming unduly heated, thereby insuring the continuous operation of the mold. It will of course be understood that the several mold-sections may be formed either with or without the water-passages and that any suitable locking device may be employed for clamping the sections together instead of the links and clamping-screws shown.
- In operation when it is desired to pour, cast, or otherwise mold one or more sash-weights the movable mold-sections are drawn together and securely fastened by placing the link over the locking-lugs and tightening the clamping-screws. The molten metal is then poured or otherwise introduced into the basins, from whence it flows through the gates 11 into the molding compartments or chambers. The sections 5 and 6 are then released and moved laterally to inoperative position by inserting a bar in the recess 26 and exerting a lateral pressure thereon, as before stated, thereby permitting the several sash-weights to be conveniently removed. Attention is called to the fact that the base of the stationary mold-section is made relatively wide with respect to the movable sections, thereby affording a support for the latter when in both open and closed positions.
- From the foregoing description it will be seen that there is produced an extremely sim-

ple and inexpensive mold by means of which center-hung sash-weights may be quickly and conveniently manufactured.

Having thus described the invention, what is claimed is—

In a mold, a stationary mold-section provided with a vertically-disposed eye-forming core and defining a smooth unobstructed bearing-surface on each side of the core, a pair of movable mold-sections slidably mounted on the bearing-surface of the stationary section and each provided with a vertical recess adapted to register with the recess in the adjacent section when said sections are in closed position, said stationary mold-section being of sufficient width to form a support for the movable sections when in both open and closed positions, a core projecting inwardly from one of the movable sections for engagement with the eye-forming core, longitudinally-disposed lugs formed integral with the movable sections and provided with inclined recesses adapted to receive an operating-tool for adjusting the movable sections to open and closed positions, spaced ears projecting laterally from the base of each movable section and disposed in alignment with the lugs, rollers journaled in said ears and adapted to engage the smooth bearing-surface of the stationary mold-section, and means for clamping the mold-sections in closed position, there being a passage formed in the stationary section beneath the eye-forming core to permit the circulation of a cooling medium and a plurality of passages formed in the movable sections and opening at each end through the side walls of said sections.

In testimony that I claim the foregoing as my own I have hereto affixed my signature in the presence of two witnesses.

LOUIS H. KNAPP
